ELECTRIC IGNITION SYSTEM

Ludvig P. Kongsted, Longmeadow, Mass., assignor to American Bosch Corporation, Springfield, Mass., a corporation of New York

Application January 23, 1937, Serial No. 121,932

3 Claims. (Cl. 123—148)

This invention relates to systems for igniting and starting internal combustion engines, and more particularly to a system which incorporates a battery and an externally excited magneto in combination.

The battery systems for starting and igniting as commonly employed in automotive use at the present time supply a greater ignition current and spark at starting than does a magneto ignition system. The low rotational speeds at which a magneto is driven during the engine starting operation produce a relatively small ignition current. Once the engine is started, the current output of the magneto increases rapidly with increase of rotational speed up to a certain range beyond which the primary current remains practically constant due to the inherent characteristics of the generating circuit. Thus sparks of approximately the same intensity are delivered at all operating speeds of the engine. The converse is true of the battery ignition systems which inherently become inefficient at high engine speeds due to the decrease in the time period of contact closure of the interrupter in the primary circuit of the ignition coil. The invention herein described provides means for employing a battery starting and ignition system to start the engine into operation under its own power, and to subsequently employ a magneto ignition system during the normal operation of the engine. It will be appreciated that a starting and ignition system which combines the merits of the foregoing described systems will provide better engine performance at high speed and easier starting than either system singly.

It is an object of this invention, therefore, to provide a starting and ignition system for internal combustion engines which is more efficient in the starting period and during the operation of an engine.

Another object is to provide starting and ignition means which incorporate in a single system the merits of the battery and of the magneto systems.

Another object is to provide a starting and ignition system which is more simple in design and economical in construction.

A further object is to provide a starting and ignition system which functions as a battery system during the engine starting period and as a magneto system subsequently.

Still a further object is to provide a combined battery and magneto type ignition system in which the magneto field excitation is supplied by the battery and in which the magneto primary

and secondary coils function as a battery energized ignition coil during the engine starting period.

Other objects and advantages will in part be specifically stated and in part be obvious when the following specification is read in connection with the drawing, in which:

Fig. 1 is a front elevation of the magneto employed in the improved ignition system; and Fig. 2 is a diagrammatic view of the ignition system and related circuits.

Referring in more detail to Fig. 1, the numeral 1 indicates a coil comprising a primary and a secondary winding, and having a laminated core 2 which is supported on laminated pole pieces 3. 15 Field windings 4 are carried on core members 5 which are supported between the pole pieces 3 and 6. A rotatable flux distributor 7 is mounted in the circular opening defined by the pole faces 8. While a four pole magneto is illustrated and described it will be obvious that the invention may be employed in connection with magnetos having a different number of poles.

In Fig. 2 is illustrated a schematic wiring diagram of the present starting and ignition system, employing a battery excited magneto as above described and in which like parts bear the same reference numerals as in Fig. 1. There is shown a battery 9 having one terminal connected to an ignition switch 10.

A conductor 11 leads from the switch 10 to one end of the series connected field windings 4, the free end of which is connected to ground to complete a return circuit to the battery 9. A series starting motor 12 has its armature connected to ground on one side through the winding 13, and the other side is connected through the winding 14 and a conductor including a normally open starting switch 15 to the ungrounded terminal of the battery 9.

A conductor 16 connects the winding 14 with the primary winding of coil 1, the other end of which is connected by conductor 17 to an interrupter lever 18 carrying a contact 19. Cooperating with the movable contact 19 is a grounded stationary contact 20.

A cam 21 operates the interrupter lever 18 in the usual manner, and the customary condenser 22 is connected in shunt across the contacts 19 and 20. A conductor 23 connects the secondary winding of the coil 1 with the distributor 7.

The secondary winding of the coil 1 is connected to any suitable distributor (not shown) which distributes ignition current to the spark plugs of an associated internal combustion engine.

In the operation of the system, the ignition switch 10 is closed and the magneto field windings 4 are energized through the field windings 4 and the primary winding of coil 1. The primary winding of coil 1 is connected in series with the distributor 7 and the secondary winding of coil 1. The secondary winding of coil 1 is connected to the distributor 7. The distributor 7 distributes ignition current to the spark plugs of an associated internal combustion engine.

ings 4 are energized by the battery 9. The starting switch 15 is closed to operate the starting motor 12 and turn over the associated engine, not shown. The primary winding of the coil 1 is connected to the battery 9 through the starting switch 15 and conductor 16, and through conductor 17 to the interrupter 18. The interrupted current in the primary winding of coil 1 produces a high voltage ignition current in the secondary winding which is led in proper timed relation to the engine spark plugs. The flux distributor 7 of Fig. 1 is being rotated by the engine, and as the field windings 4 are energized the magneto generates alternating current which during the cranking of the engine is of small magnitude compared with the current drawn directly from the battery through conductor 16. Sparks of practically the same intensity are therefore delivered to all of the spark plugs during the cranking period. When the engine starts under its own power, the starting switch 15 is opened, disconnecting the starting motor 12 and the primary winding of coil 1 from the battery 9, and the ignition system operates as an externally excited magneto system. The primary circuit under magneto operation is from the primary winding of coil 1 through conductor 16 and the low resistance windings 14 and 13 of the starting motor 12 to ground, through interrupter contacts 20 and 19, and conductor 17 to the other end of the primary winding. An engine driven generator may be connected as well known in the art to maintain the charge of the storage battery 9.

It is to be expressly understood that the drawing herein is intended solely for the purpose of illustrating the invention and is not to be construed as in any way limiting the scope, or the various possible applications of the invention. Many changes and modifications may be made by anyone skilled in the art without departing from the subject matter of the invention as expressed in the following claims.

Having described the invention, what is claimed is:

1. In ignition apparatus for an internal combustion engine, means for successively providing battery ignition and magneto ignition for said engine comprising a magneto having a primary winding and a secondary winding, a circuit permanently maintaining one end of said windings at a common potential, a battery, means including a switch for conducting interrupted battery current through said primary winding and deriving battery ignition current from said secondary winding, exciting windings on the stator member of said magneto and having one end thereof permanently connected to ground, a connection between said battery and said exciting windings including a switch independent of said

first mentioned switch for energizing said exciting windings during both successive periods of battery and magneto ignition, a rotatable flux distributor in said magneto, and means for conducting interrupted magneto-electric current through said primary winding and deriving magneto ignition current from said secondary winding. 5

2. In ignition apparatus for an internal combustion engine, means for successively providing 10 battery ignition and magneto ignition for said engine comprising a magneto having a primary winding and a secondary winding, a circuit permanently maintaining one end of said windings at a common potential, a battery, a connection 15 including a switch between said battery and said circuit, means for conducting interrupted battery current through said primary winding and deriving battery ignition current from said secondary winding, exciting windings on the stator member of said magneto and having one end thereof permanently connected to ground, a connection between said battery and said exciting windings including a switch independent of said first mentioned switch for energizing said exciting 20 windings during both successive periods of battery and magneto ignition, a rotatable flux distributor in said magneto, and means for conducting interrupted magneto-electric current through said primary winding and deriving magneto ignition current from said secondary winding. 25

3. In ignition apparatus for an internal combustion engine, means for successively providing 30 battery ignition and magneto ignition for said engine comprising a battery, a starting circuit connected to said battery and having a normally open switch therein, a magneto having a primary winding and a secondary winding, a permanent connection joining one end of said windings with the normally dead terminal of said switch, means 35 for conducting interrupted battery current through said primary winding when said switch is closed and deriving battery ignition current from said secondary winding, exciting windings 40 on the stator member of said magneto and having one end thereof permanently connected to said battery, a connection between the other end of said exciting windings and said battery including a second switch independent of said first mentioned switch for energizing said exciting windings during both successive periods of battery 45 and magneto ignition, a rotatable flux distributor in said magneto, and means for conducting interrupted magneto-electric current through said primary winding and deriving magneto ignition current from said secondary winding. 50
